DESIGN FOR A WIRE STITCHING MACHINE

George H. Harred, Warwick, R. I., assignor to
Boston Wire Stitcher Company, Portland,
Maine, a corporation of Maine

Application May 11, 1934, Serial No. 51,744

Term of patent 14 years

To all whom it may concern:

Be it known that I, GEORGE H. HARRED, a citizen of the United States, residing at Warwick, in the county of Kent and State of Rhode Island, have invented a new, original, and ornamental Design for a Wire Stitching Machine, of which the following is a specification, reference being had to the accompanying drawing, forming a part thereof, in which:

Fig. 1 is a front elevation in perspective of the machine showing my new design; and
Fig. 2 is a rear elevation in perspective.

I claim:

The ornamental design for a wire stitching machine substantially as shown.

GEORGE H. HARRED.
